UNITED STATES PATENT OFFICE.

ROBERT M. CLARK, OF NEWTON CENTER, MASSACHUSETTS, ASSIGNOR TO CENTRAL RAILWAY SIGNAL COMPANY, OF PITTSBURGH, PENNSYLVANIA, A CORPORATION OF NEW JERSEY.

RAILWAY SIGNAL-FUSEE.

1,107,034.

Specification of Letters Patent. Patented Aug. 11, 1914.

Application filed May 5, 1914. Serial No. 836,545.

To all whom it may concern:

Be it known that I, ROBERT M. CLARK, a citizen of the United States, residing at Newton Center, in the county of Middlesex and State of Massachusetts, have invented certain new and useful Improvements in Railway Signal-Fusees, of which the following is a specification, reference being had therein to the accompanying drawing.

My invention relates to improvements in railway signal fuses, and the present invention pertains to an improved manner of securing a plug within the end of the fusee tube, and it is more particularly intended for holding the plug which contains a spike.

It is well-known to those skilled in the art that certain tubes of railway time burning signal fusees contain at one end a spike through the medium of which the fusee is supported in an upright position while burning, the spike being driven into a railway tie or into the railroad bed; and it is also well-known to those skilled in the art that these spikes are carried by a plug, sometimes wood and sometimes metal, and that these plugs fit within the end of the fusee tube. Heretofore, these plugs have been generally glued into the ends of the fusee tubes, though, in some instances, when the plug is wood, it may be connected by tacks driven through the wall of the tube into the wood plug, and by combined glue and tacks.

The object of my present invention is to so construct the end of the fusee tube and the plug that the plug is firmly connected to the end of the tube without the use of glue or tacks, and in a manner to absolutely prevent the possibility of the plug being detached from the fusee.

In the accompanying drawing: Figure 1 shows a portion of a paper or fiber tube of a railway time burning signal fusee, showing one end of the tube doubled backward and turned inward to form a double wall. Fig. 2 is a sectional view showing the completed fusee with the improved plug and double wall tube. Fig. 3 is a perspective view of the completed fusee.

Referring now to the drawings in which like reference letters refer to similar parts, 1 is a paper or fiber tube which contains the burning composition 2. This tube is composed, as usual, of a suitable grade of paper. In carrying out my invention, I

provide one end of the tube with an inner annular shoulder or flange 3, which constitutes at that end of the tube a double wall, and preferably this double wall is formed by turning backward and inward the tube 60 itself, as clearly shown in Figs. 1 and 2. The plug to be used with this flanged or shouldered end of the tube has a body-portion 4, of a size to fit within the opening at the double wall end of the tube, as clearly 65 shown in Fig. 2, and the inner end of the plug is provided with a laterally extending shoulder or flange 5, which is preferably, though not necessarily, annular and unbroken. This flange 5 fits against the shoulder or flange formed by the double wall 3, and the composition 2 is against the inner end of the plug and serves to hold it permanently in position. Those skilled in this art know that in railway time burning 70 fusees the composition 2, is tightly packed within the tube 1 so that the composition forms a substantial and solid support for the plug to prevent it from being forced inward within the tube 1. This plug carries a spike 6, when a spike is to be used, and this invention is particularly intended for use with a spiked plug. Preferably the double wall 3 is first formed on the tube 1 and the plug passed into the tube from the 75 opposite end and pushed therethrough until its flange 5 abuts against the inner end of the double wall 3. Then the composition 2 is packed within the tube. However, I 80 wish it understood that the composition may be packed within the tube and then enough of it removed or drilled out of the tube to receive the plug, and then the wall of the tube turned inward and forced down into the position shown in Fig. 2, by a 85 suitably constructed rotating tool. The plug may be formed of wood, metal, cement, or any other suitable material, without departing from the spirit and scope of my present improvement.

While my invention is particularly intended for use in connection with railway time burning signal fusees, I wish it understood that it may be used in connection with fireworks, where it is desired to support 90 them in an upright position through the medium of a plug. It will also be understood that the spike 6, when the plug is of metal, is a nail cast within the plug, though the nail may be cast or formed in- 95 100 105 110

tegral with the plug when the plug is made of metal.

Having thus described my invention, what I claim and desire to secure by Letters Patent is:

1. A railway signal fusee, comprising a paper tube having one end doubled inward to form an inner wall, and a plug having at its inner end a flange fitting the interior of the paper tube and abutting against the inturned wall, the plug having a body-portion extending within and fitting against the inner wall, and a spike carried by the plug and projecting beyond the tube, for the purpose described.

2. A railway signal fusee comprising a paper tube having one end doubled inward to form a relatively elongated double wall,

and a plug having an elongated portion embraced by and tightly fitting the said doubled wall, the inner end of the plug having a projecting flange fitting within the tube and abutting against the end of the wall and the outer end of the plug carrying a projecting spike, and a signaling compound within the tube and abutting against the end of the plug, all combined for the purpose described.

In testimony whereof I hereunto affix my signature in the presence of two witnesses.

ROBERT M. CLARK.

Witnesses:

JOHN W. EDMANDS,
ARNOLD MACKINTOSH.
